UNITED STATES PATENT OFFICE.

KARL STEINBECKER, OF CHARLOTTENBURG, NEAR BERLIN, GERMANY.

DEVICE FOR DRIVING INTERNAL-COMBUSTION ENGINES.

1,235,611.

Specification of Letters Patent.

Patented Aug. 7, 1917.

Application filed October 14, 1913. Serial No. 795,164.

To all whom it may concern:

Be it known that I, KARL STEINBECKER, subject of the German Emperor, residing at Charlottenburg, near Berlin, Germany, have 5 invented new and useful Improvements in Devices for Driving Internal-Combustion Engines, of which the following is a specification.

The present invention relates to the driving of internal combustion engines in which, shortly before the end of the compression stroke and at the beginning of the expansion stroke, the fuel is brought into the nozzle, in the form of a narrow neck, of a retort 15 which is in permanent connection with the working cylinder, and the relatively small stream or volume of fuel within the narrow neck may be cooled as equitably as possible.

The purpose of this arrangement is to generate 20 in the retort a very powerful auxiliary explosion so that the fuel is as perfectly as possible dispelled to the cylinder and burnt. The present invention perfects this method of working in several respects. Firstly, the 25 cooled fuel which is to be fed into the neck of the retort is forced in a sloping or tangential direction against the wall of the nozzle, and the nozzle is formed as a double injection channel, which, with the same section 30 on both sides, has such a length that the fuel is accelerated to the speed of the flowing gases as far as the outlet end, in order to obtain in both directions the highest attainable outlet and dispelling energy. Then 35 the cooling extends in a special manner to the nozzle and to a part of the retort. Further, other means are provided in order to completely prevent the dripping of the fuel out of the pressure piping and thus the 40 harmful pre-ignition in the retort. Finally, means are provided that even when starting, a powerful auxiliary explosion takes place by means of a flame jet operated by hand, oxygen being preferably introduced or by 45 means of a substance containing oxygen.

In the drawings—

Figure 1 is a longitudinal section of a device constructed in accordance with the present invention;

50 Fig. 2 is a detail longitudinal sectional view on an enlarged scale;

Fig. 3 is a longitudinal section of a slightly modified construction, and

55 Figs. 4, 5, 6, 7 and 8 are similar views of still further modifications.

As shown in Fig. 1, the working cylinder *a* is in permanent connection with the retort *b* through the nozzle channels *c*. On the upward stroke of the piston the air is compressed above the self-igniting temperature 60 of the fuel, part of same going to the retort. If now toward the end of the compression stroke the fuel is distributed through the channels *d* and *e* into the channel *c*, then the first fuel particles are taken along to the 65 retort, are ignited in the hot air and the consequent increase of pressure drives the remainder of the fuel into the cylinder, where it is likewise burnt by self-ignition. The combustion both in the retort and in the 70 cylinder is therefore effected by self-ignition. It is now of decisive importance that the air should be burnt out of the retort as completely as possible, so that a sufficiently 75 large spraying or dispelling energy is attained. Now the fuel is, however, vaporized and burnt as soon as it comes in contact with the current of air in the channel or the air in the retort. It must be added that the 80 highly overheated combustion gases of the retort heat the channel which they flow through and also the retort walls to a temperature which is several times that of the self-igniting temperature of the fuel.

From this it results that the fuel cannot 85 find its way in sufficient quantity into the retort, because the first fuel particles which burn in the channel and at the opening to the retort produce an immediate increase of pressure so that the gases are forced back 90 too early to the cylinder thus preventing a sufficient quantity of fuel reaching the retort. It is therefore of the greatest importance to drive the fuel in such quantities into the hot air of the retort and to mix it 95 with same before self-ignition occurs, that on the self-ignition and reversal of direction of the gases, the requisite spraying energy is attained.

According to the present invention this is 100 attained by the fuel being injected through the channel *e* to the retort. By this arrangement it is attained that the velocity energy of the fuel which is given to it by the fuel pump, attains the maximum attainable value 105 by means of the velocity energy of the flowing gases. The velocity of the gases is several times greater than that which can be given to the fuel. On the other hand the mass or specific weight of the fuel is much 110

greater than that of the flowing gases. The energy is determined, however, by mass and velocity. The energy of the fuel can therefore be quite considerable in comparison 5 with the energy of the gases. If the fuel were injected opposite to the direction of the gases or transverse to same then its own energy must firstly be entirely destroyed and the fuel accelerated afresh. By this means, 10 however, the energy of the gases is considerably reduced, so that the fuel is not driven far enough into the retort before self-ignition takes place, although in this case an extremely good spraying is obtained, but 15 this does not come into question for the first part of the working cycle because in the small retort space there exists the most violent eddies which, on the self-ignition and reversal of movement taking place are still 20 further increased. For this part it is only important that the fuel should be present in sufficient quantity everywhere in the retort.

In the second part of the working cycle, 25 the spraying toward the cylinder, the fuel is injected directly opposite to the flow of gas. As in this case the fuel must be distributed into a large space a perfect spraying is necessary. As, however, during the 30 first part of the working cycle a sufficient strength has been given to the auxiliary explosion, there is sufficient energy at disposal for the spraying or dispelling and distribution of the fuel to the cylinder.

35 The fuel can be injected directly toward the retort or in a direction sloping or tangential against the walls. It can during this operation be led directly into the channel itself.

40 Instead of the one fuel channel e , several such canals may be arranged in the circumference of the main channel e .

It is now of the greatest importance, that 45 the fuel arrives in the channel not only in the exact intended time, but it must be taken along by the current at that moment in which it enters the channel, which current takes it either to the retort or to the cylinder, because each fuel particle which remains in 50 the channel would disturb or render impossible the working process. If now, during the compression stroke in which only pure air should be fed to the retort, fuel were taken along which had remained in the 55 channel from the foregoing working cycles, then the auxiliary explosion in the retort would occur at the wrong time, so that the working fuel would find no spraying or dispelling energy or only an insufficient quantity. If now on the other hand, a correctly timed auxiliary explosion being presumed, the working fuel is sprayed too late to the working cylinder, then the oil in the cylinder will also be delayed in its combustion and 65 with a bad efficiency.

The present invention has now the purpose of reliably preventing fuel remaining in the spraying channel. For this purpose the channel is formed as a double-ended injection channel of equal or nearly equal sectional area. 70

The nozzle channel c which connects the retort b and the cylinder a has the form of a cylindrical tube in whose center, say at e' , which first flows from the cylinder to the retort, and after the auxiliary explosion from the retort to the cylinder, may be imagined as a number of parallel currents of equal velocity (Fig. 1) as a conversion of 80 the excess pressure into velocity takes place at the entry to the channel.

If now a drop of fuel is inserted into the channel (Fig. 3) then at this point the channel will be constricted and the conversion 85 of energy will be transferred from the entrance to the channel to this narrowest point in the proper proportion. The pressure in the channel behind the drop of fuel hereby drops from p_2 to p_1 . If the drop has the 90 sectional area f , then it is accelerated toward the retort or toward the cylinder with the force $(p_2 - p_1) f$. In order, however, that the drop of fuel may assume the velocity of the flowing gases, the acceleration must 95 be effected during a determined period and for a determined length of path. This is attained by the channel having a determined length and a constant or nearly constant sectional area. By this means the fuel, as far 100 as the opening of the channel, remains under the accelerating effect of the gas current, for if the drop of fuel or a detached part of same were to remain attached to the wall on its passage, then there would immediately 105 be caused at this point a reduction in area and consequently an immediate pressure action on the drop.

If the channel were to be reduced or increased in diameter toward the end, then the 110 fuel would only be completely "gripped" by the current of air at the narrowest point. A larger portion of the fuel would be forced sidewise and come too late or not at all into the current of air so that the working process 115 would be impossible.

According to the present invention, by 120 means of the formation of the channel as a double-ended injection channel with constant or nearly constant area and of such a length that the fuel attains the requisite outlet velocity, is the action attained.

The two branches of the channel need not necessarily lie in one axis or direction.

The form of the channel section is determined by the form of the combustion space. If, for instance, the combustion chamber is of disk shape into which the fuel is injected sidewise, then the channel will expand toward the cylinder in order to obtain a 130

broader stream. It is essential, however, that the sectional area remains constant and the alteration is gradual so that the stream of gas may adapt itself to same. It has in the foregoing been presumed that the gas stream consists of a number of streams of smaller diameter (of a "bundle" of current "threads") which have equal velocity. This assumption is only true for the ideal case of

10 frictionless walls. As a matter of fact the friction of a wall has a delaying effect upon the outer current "threads," which effect is the greater the rougher the wall. Consequently the smallest fuel particles can remain attached to the walls as soon as their power of adhesion is greater than the force of acceleration. These smallest particles become firmly attached and carbonize under the action of the hot gases, gradually obstructing the nozzle.

15 This undesirable effect is obviated by the walls of the retort having a smooth polished surface, being provided with a glaze, a coat of enamel, an electrolytic metallic coating or the like.

20 The inventive idea disclosed at the commencement, to obtain as powerful a spraying or dispelling energy as possible by the fuel being injected toward the retort so that before the self-ignition occurs said fuel has penetrated as far as possible into the retort, can now be more perfectly carried into effect.

25 By means of the combustion in the retort and in the working cylinder and further on account of the fact that the highly overheated combustion gases constantly flow through the channel, the channel and the retort are heated far beyond the permissible temperature. As soon therefore, 30 as the fuel enters into the channel and the beginning of the retort, the combustion and the pressure-increase begin and the reversal of the flow of current prevents the entry of a sufficient quantity of fuel into the retort.

35 This pre-ignition is prevented according to the present invention, and a powerful auxiliary explosion is obtained, by the channel *e* (Fig. 1) being cooled to such an extent by the circular space *f* and the neighboring retort wall at *g*, that the fuel enters the channel and the entrance to the retort in liquid form. Between this taking place and the vaporization of the fuel there exists such a period that the fuel can 40 penetrate in sufficient quantity the whole interior of the retort and is only ignited in the far end of same. The far end of the retort remains uncooled in order to insure self-ignition.

45 For this purpose a heat insulating body of corresponding form is provided in the rear end of the retort, which said body is held constantly at high temperature and which may be, for example, in the form of an incandescent pipe *h* (Figs. 1, 3, 4 and 7).

As the possibility of carrying the process into effect is dependent upon the certain self-ignition, the air when starting the machine must be so hot when arriving in the auxiliary space, that the self-ignition is insured. 50 As the cold metal parts of the retort and of the channel absorb a fairly large quantity of heat from the air, the igniting capability would be very doubtful, if these parts were to be cooled when starting. The cooling 55 medium, water, mercury or the like, is therefore replaced by a heat-insulating material, for instance, air. This is preferably effected in such a manner that when starting, the feed piping for the cooling medium is shut 60 off, while on the other side there is free exit from the cooling space so that this space is filled with air which acts as a heat-insulating material. In Fig. 1 an automatic overflow for effecting this free exit is illustrated. 65 The water which flows out of the cover at *i* arrives partly through the overflow *k* to the cooling space *g* of the retort and of the channel *f* from whence it can flow out freely through *l*. As soon therefore as the cover 70 cooling device is shut off, the water flows away from this piping, as the piping at *m* is open to the atmosphere, and these spaces are filled with air. When the main cooling 75 system is again put into action after the machine has started, these spaces are filled with water through the overflow and in order to obtain efficient cooling or insulation, the walls of the nozzle channel are 80 made as thin as possible.

85 For fuels which vaporize and burn with different degrees of difficulty, the moment is determined by correspondingly adjusting the cooling device, at which the self-ignition takes place, and consequently also the 90 amount of spraying or dispelling energy.

95 Under certain circumstances, when the hot air from the working cylinder is cooled to such a large extent on entering the retort channel that a pre-ignition in the channel 100 or entrance of the retort is prevented, an undesirable further cooling of the air takes place by the injected fuel, because the vaporizing heat of the fuel is very great in comparison with the quantity of heat which this 105 weight of air can give off. Care must be taken that the taking away of heat from the air above all takes place at the entrance of the cooled channel before the pressures and the temperatures have been converted into 110 velocity. In the channel itself where a conversion into velocity takes place, the temperatures are relatively low. High temperatures do not exist until the middle part 115 of the retort has been reached, where the 120 velocity is again converted into pressure and temperature, but which higher temperatures are brought to the correct temperature by cooling the retort.

125 The fuel will therefore for the greater 130

part enter the retort in liquid form and, in consequence, of the alterations in velocity will partly condense to drops of liquid which are then difficult to vaporize and 5 spray or dispel. Consequently an excess quantity of fuel must arrive in the retort in order to at least use up the air in the same. As now the retort can empty itself through the channel only by expansion, 10 there remains in the retort residue of burnt oil vapors which in the next cycle mix with fresh air and ignites in the rear portion of the retort which is above the self-ignition temperature. This preliminary combustion 15 causes a part of the air for the dispelling energy to be lost and because of the expansion of these combustion gases, the entrance of a further portion is prevented. The maximum attainable quantity of air is therefore not at 20 disposal for the dispelling energy so that the engine is not employed to its full efficiency and the cylinder diagram is not the most favorable which may be attained.

These disadvantages are overcome by the 25 requisite vaporizing heat being added to the flowing over mixture of oil and air, in the rear part of the channel and in the front part of the retort, by these parts being raised to the necessary temperature which 30 of course lies below that of self-ignition.

As shown in Fig. 3 this is effected, for example, by the parts *n* being maintained below the self-igniting point. The retort is greatly heated by the combustions in the 35 retort, whereby the most preferable temperatures can be secured by the flow of heat to the cooled portions, for example, by the cooling ring *g'*, Figs. 3 and 4, in the middle part of the retort being more or less raised. 40 The cooling ring may be divided or the cooling medium made hotter or colder. By this means it is possible to adapt the heat temperatures for oil to the most variable vaporizing heats. In those motors in which 45 the flow of heat is greater than the heat conveyed from the retort, for example, in slow running four-stroke engines, these parts must as a matter of fact be heated. This is effected for example, as shown in Fig. 4, 50 in which the upper part of the channel is surrounded by a circular space *o* with preferably thin walls, which is connected with the working cylinder through the channels *q* and *r*. These parts are preliminarily 55 heated by the compression heat from the working cylinder before the injection of the fuel begins.

These parts may of course be kept at the requisite temperature by other means, 60 for example, by means of heat-insulating material.

In the arrangement illustrated, there are two cooled parts, viz., the entrance to the channel and the middle part of the retort, 65 and two heated parts, viz., the rear portion

of the retort which is kept above self-ignition temperature and the rear part of the channel together with the entrance to the retort which latter parts are kept heated but are below the self-ignition temperature. 70 By means of the cooling the self-ignition is delayed until the air in the retort is saturated with oil vapor by means of the heating between the coolings which vaporize the injected oil without any residue and dispels same, and by the overheating in the rear portion of the retort the self-ignition is effected with certainty as soon as the intermixing is complete.

It is important to generate as powerful 80 an auxiliary explosion as possible and an essential condition to this end is that the fuel is injected at the exact moment intended. It is, however, a peculiarity of those working methods which work without 85 injected air, that the fuel in the pressure piping is closely contiguous to the channel or working cylinder and that it drips out of the piping at the wrong time and under the influence of the hot flowing gases and their suction action. Even when the channel is carefully cooled and limited to the 90 smallest volume, this unfavorable action cannot be entirely prevented, especially as in consideration of the quantity of fuel to 95 be injected, a certain pipe diameter is necessary.

The invention overcomes these difficulties by the fuel being expelled from the front end of the pressure piping after each injection 100 so that even under the influence of great heat or pressure variations, the fuel can no longer drip out of the piping.

This method of working is attained, for example, as shown in Fig. 1 by the throttle bore *s* branching off from the front end of the pressure piping *d* through which throttle bore the fuel remainder is blown back into the fuel receiver. The adjustment of the throttling is effected by the throttle screw *t*. 105 In place of this latter a valve *u* may be provided, as shown in Fig. 5, which shortly after completion of the injection is operated by the lever *v* and cam *w*.

A similar effect is obtained as shown in 115 Fig. 6 by the fuel plunger *x* itself sucking back a portion of the quantity of oil in the pressure piping, said plunger pushing open the pressure valve *y* toward the end of a pressure stroke, so that on the immediately following suction stroke the fuel flows back to the pump until the pressure valve is seated on its seating. The plunger and its controlling mechanism must, however, be adjusted exactly to the position of the pressure valve. 120

Fig. 7 shows the most simple solution of this difficulty. The pressure valve *y* is provided at *z* with a piston which is ground for a certain length in its guide. As soon now as the pump feeds, the pressure valve is 125 130

raised from its seating until the ground-in piston has emerged from its guide. From then onward the fuel can flow freely past the piston to be injected. After the injection is complete the valve is closed by spring pressure. A further movement of the valve is prevented by the fuel in the pump which cannot pass around the piston. Only at that moment in which the plunger moves back, 10 which occurs preferably immediately after the injection is complete, can the valve move toward its seat and during this time the valve sucks a quantity of fuel back from the piping which corresponds to the volume of 15 the ground-in piston. This back-suction is assisted by the strong gas pressure in the retort which in this moment presses on the column of fuel. The position of the plunger is thereby perfectly independent of the position of the valve. The opening and closing of the plunger is effected to a certain extent by the form of fuel and thus, independent of the load, etc., drawing back the excess fuel lying within the supply pipe after an 25 explosion.

The means hereinbefore characterized serve during the normal working of the machine to attain a powerful auxiliary explosion in the retort and thus a good dispersion 30 to the working cylinder. The following improvement has for its object to generate a powerful auxiliary explosion of this kind even when starting the cold engine.

As engines of the type under consideration 35 require a high degree of compression in order to attain the required igniting heat, it is impossible to crank-over the engine by hand against compression. If the compression is highly reduced, then the self-ignition temperature of the fuel will not be reached and the engine will not start. It must also be added that the cold cylinder walls take heat from the compression air. In the so-called incandescent-head motors, the incandescent- 40 head is heated from the outside to such a temperature that on starting the engine the self-igniting temperature will be attained. The heating of such a large portion of the engine is, however, extremely inconvenient.

50 The present invention obviates these difficulties by a hot flame jet being ignited immediately in the working cylinder or in the retort which flame heats the compression air to such an extent that on the fuel entering 55 self-ignition takes place and the machine starts.

It is of importance that the flame is continued until the self-ignition temperature is with certainty attained.

60 In Fig. 1 and to a greater scale in Fig. 8 the invention is illustrated by way of example.

In the retort *b* is a heating cartridge *A*, preferably composed of gunpowder although 65 any other suitable material may be used

which is inserted by means, for instance, of a bayonet or eccentric securing device as illustrated. At the front end it is provided with an igniting mass *B* which on contacting with the point *c* ignites the cartridge. 70 The contacting is effected by hand or automatically from the outside by means of the striking bolt *D*.

As the local heating by means of the flame is of importance in this process, it is preferable to surround the cartridge by a heat-insulating body of corresponding shape, which rapidly absorbs the heat and retains same; for instance a cartridge may be inserted into the incandescent tube. 75 80

Driving oils which have a high self-igniting temperature possess, however, the property that at or near atmospheric pressure they are with difficulty ignited, for instance under the low compression when cranking up, even with a hot flame and further, the combustion proceeds slowly and imperfectly. The energy generated is scarcely sufficient to carry the machine over the first full compression stroke. These disadvantages are 85 90 overcome by oxygen or a substance containing oxygen is fed to the heating flame in such quantity and in such proportion that a strong auxiliary explosion is with certainty attained. Any suitable means for this purpose may be employed. In the presence of oxygen or a substance which contains the former to a certain degree of superfluity, oils of the kind under consideration will burn even with normal pressures and normal 95 100 commencing temperatures.

On the other hand by means of a corresponding determined and added quantity of oxygen, the oxygen of the air in the cylinder is increased to such an extent that the desired explosive energy can be reached. In order to prevent too sudden ignitions, the oxygen must be added in the correct quantity and at the right time and in the correct 105 dilution.

The oxygen or the substance containing same can be inserted simultaneously with the heating cartridge. A specially simple construction results when the oxygen or substance containing same is mixed directly 110 with the powder of the cartridge, so that on the same burning the oxygen is released.

Fig. 8 illustrates a cartridge of this kind. The powder *B* in the rear portion of the cartridge, which is ignited in a known manner by the striking bolt *D* has the property that on burning it gives a hot flame which burns slowly and brings the neighboring parts to a high temperature. On combustion the contained oxygen is forced through the retort toward the channel. If fuel is simultaneously injected, particles of fuel and oxygen meet together and are ignited by the flame. The consequent explosion disperses the oxygen and the remainder of the fuel together 115 120 125 130

with that in the cylinder whereby also in this latter a powerful explosion is caused.

Having now described my invention what I claim as new and desire to secure by Letters Patent is:—

- 5 1. In an internal combustion engine, the combination with a power piston and cylinder of a retort, a relatively narrow passage connecting the cylinder and the retort, and means for introducing fuel directly into the said narrow passage in the direction of the retort during the compression stroke.
- 10 2. In an internal combustion engine, the combination with a power piston and cylinder of a retort, a relatively narrow passage connecting the cylinder and the retort, and means for introducing fuel directly into the said narrow passage at an inclination thereto and in the direction of the retort during the compression stroke.
- 15 3. In an internal combustion engine, the combination with a power piston and cylinder of a retort constituting an auxiliary combustion chamber and having a relatively narrow inlet in constant communication with the cylinder, means for introducing fuel into the retort during the compression stroke, means for cooling the central part of the retort, and means for heating the upper part
- 20 4. In an internal combustion engine, the combination with a power cylinder and piston of a retort having a relatively narrow inlet in constant communication with the cylinder, means for introducing fuel into the retort during the compression stroke, and starting means for producing a jet flame in the retort to unite the fuel therein and heat the retort.
- 25 5. In an internal combustion engine, the combination with a power piston and cylinder of a retort having a relatively narrow inlet in constant communication with the cylinder, means for introducing fuel into the retort at the said inlet during the compression stroke, and starting means for producing a jet flame in the retort and for simultaneously supplying oxygen to the retort.
- 30 6. In an internal combustion engine, the combination with a power piston and cylinder of a retort having a relatively narrow inlet in communication with the cylinder, means for introducing fuel into the retort at the said inlet during the compression stroke, and starting means at one end of the retort for producing an igniting and heating flame in the retort.
- 35 7. In an internal combustion engine, the combination of a power piston and cylinder of a retort, a relatively narrow channel connecting the retort and cylinder, said channel having smooth glazed inner walls, and means for introducing fuel directly into said channel during the compression stroke.

8. In an internal combustion engine, the combination of a power piston and cylinder of a retort, of a relatively narrow passage connecting the retort and cylinder, said passage being of substantially the same cross sectional area throughout its length, a fuel conduit leading into said passage at an inclination thereto in the direction of the retort, and means for supplying fuel to said conduit.

70 9. In an internal combustion engine, the combination of a power piston and cylinder of a retort, a relatively narrow channel connecting the retort and cylinder, means for introducing fuel into said channel during the compression stroke, in combination with means for cooling a part of the channel and the intermediate part of the retort, and means for maintaining the upper part of the retort at a temperature above the self ignition temperature of the fuel.

75 10. In an internal combustion engine, the combination of a power piston and cylinder of a retort, a relatively narrow channel connecting the retort and cylinder, means for introducing fuel into said channel during the compression stroke, in combination with means for cooling a part of the channel and a part of the retort, and means for maintaining a part of the retort at a temperature above the self ignition temperature of the fuel, said last mentioned means comprising a heat insulating body associated with the retort.

80 11. In an internal combustion engine, the combination of a power piston and cylinder of a retort, a relatively narrow channel connecting the retort and cylinder, means for introducing fuel into the said channel during the compression stroke, means for cooling the lower part of said retort to maintain the same below the self igniting temperature, and means for maintaining the upper part of the retort above the self ignition temperature of the fuel.

85 12. In an internal combustion engine, the combination with a power piston and cylinder of a retort, a relatively narrow channel connecting the retort and cylinder, means for introducing fuel into the retort during the compression stroke, a jacket for said channel, means for supplying air to the said jacket upon the starting of the engine, and means for supplying a cooling medium to the jacket when the engine is running.

90 13. In an internal combustion engine, the combination with a power piston and cylinder of a retort, a relatively narrow channel connecting the retort and cylinder, means for introducing fuel into the channel during the compression stroke, means for cooling the entrance to the channel and the middle part of the retort, and means for maintaining the rear portion of the channel and the forward portion of the retort at high tem-

perature but below the self ignition temperature of the fuel and to maintain the rear portion of the retort above the self ignition temperature of the fuel.

5 14. In an internal combustion engine, the combination with a power piston and cylinder of a retort, a relatively narrow channel connecting the retort and cylinder, means for introducing fuel into the channel during 10 the compression stroke, means for cooling the entrance to the channel, and means for heating the rear portion of the channel entirely surrounding the same, said last mentioned means including a jacket extending 15 adjacent said portion of the channel and in communication with the cylinder.

15 15. In an internal combustion engine, the combination with a power piston and cylinder of a retort, a relatively narrow passage 20 connecting the cylinder and the retort, a fuel conduit leading to said passage, means for injecting fuel through said conduit to the said passage during the compression stroke, and for withdrawing surplus fuel from the 25 said fuel conduit.

16. In an internal combustion engine, the combination with a power cylinder and piston of a retort having a relatively narrow inlet in communication with the cylinder, 30 means for introducing fuel into the retort during the compression stroke, and means located at one end of the retort opposite the said inlet for producing a jet flame in the retort and for simultaneously supplying 35 oxygen to the retort for heating the same.

17. In an internal combustion engine, the combination with a power piston and cylinder of a retort, a relatively narrow passage connecting the cylinder and the retort, a fuel 40 conduit leading to the said channel, means for feeding fuel to the fuel conduit and for withdrawing surplus fuel from the fuel conduit, said means including a fuel supply and a pump connected with the fuel conduit and 45 said supply.

18. In an internal combustion engine, the combination with a power cylinder and piston of a retort having a relatively narrow inlet in communication with the cylinder, 50 means for introducing fuel into the retort during the compression stroke, said retort being provided with started means for igniting the mixture in the retort, and constituting a preliminary heating means for the re- 55 tort.

19. In an internal combustion engine, the combination with a power cylinder and piston of a retort, a relatively narrow inlet in communication with the cylinder, means 60 for introducing fuel into the retort during the compression stroke, said retort having means for receiving a starting cartridge.

20. In an internal combustion engine, the combination of a power cylinder and a piston 65 ton, of a retort having communication with

the cylinder, means for introducing fuel into the retort, and means for producing a combined igniting and heating flame in the retort for the starting of the engine.

21. In an internal combustion engine, the 70 combination of the power-cylinder and piston, of a retort having a communication with the cylinder, means for feeding fuel to the retort and means for producing a jet flame for heating the retort for starting of 75 the engine.

22. In an internal combustion engine, the combination of a power-cylinder and its piston, of a retort, a communication 80 between the cylinder and the retort, means for introducing fuel into the retort during the compression stroke, the said retort having a seat adapted to receive a starting cartridge, and means for igniting said cartridge. 85

23. In an internal combustion engine, the combination of a power-cylinder and its piston, of a retort, a communication between the cylinder and the retort, means for introducing fuel into the retort during 90 the compression stroke, the said retort having a seat adapted to receive a starting cartridge, and means for igniting said cartridge comprising a striking point associated with the engine and adapted to engage 95 the cartridge.

24. In an internal combustion engine, the combination of a power-cylinder and its piston, of a retort, a communication between the cylinder and the retort, means for 100 introducing fuel into the retort having a seat during the compression stroke, the said retort adapted to receive a straight cartridge, and means for igniting said cartridge, comprising a reciprocating striking 105 point, for engagement with the cartridge, an operating handle for actuating said striking point.

25. In an internal combustion engine, the combination with a power piston and cylinder, of a retort, a passage connecting the cylinder and retort, a fuel conduit leading to the retort, pump actuated mechanism for injecting fuel through the said conduit into the retort, said pump actuated mechanism 110 115 also withdrawing the surplus fuel from the conduit.

26. In an internal combustion engine, the combination with a power piston and cylinder, of a retort, a passage connecting the cylinder and retort, a fuel conduit leading to the retort, means for injecting fuel through the said conduit into the retort, said means also withdrawing surplus fuel from the conduit and comprising a cam 120 125 actuated piston.

27. In an internal combustion engine, the combination with a cylinder and its piston, of a retort, a channel connecting the retort with the cylinder, means for introducing 130

fuel to the retort, and a jacket having passages therein surrounding the channel, means for supplying air to the jacket for heating the channel walls upon the starting 5 of the engine, and means for supplying a cooling medium to the jacket after the channel has become heated.

In testimony whereof I have signed my name to this specification in the presence of two subscribing witnesses.

KARL STEINBECKER.
